UNITED STATES PATENT OFFICE.

ROBERT H. IRONS, OF HARRISBURG, PENNSYLVANIA, ASSIGNOR TO CENTRAL IRON & STEEL COMPANY, OF HARRISBURG, PENNSYLVANIA, A CORPORATION OF PENNSYLVANIA.

DESIGN FOR A METALLIC FLOOR PLATE.

Application filed April 1, 1925. Serial No. 12,979. Term of patent 14 years.

To all whom it may concern:

Be it known that I, ROBERT H. IRONS, a citizen of the United States, residing in Harrisburg, Dauphin County, Pennsylvania, have invented a new, original, and ornamental Design for a Metallic Floor Plate, of which the following is a specification, reference being had to the accompanying drawing, forming part thereof, in which—

Fig. 1 is a plan view of a portion of a metallic floor plate illustrating my design; and

Fig. 2 is a sectional view on the line 2—2, Fig. 1.

I claim:

The ornamental design for a metallic floor plate, substantially as shown.

ROBERT H. IRONS.
